EMILE LABRÉLY, OF PARIS, FRANCE, ASSIGNOR TO PATHÉ FRERES PHONOGRAPH COMPANY, OF NEW YORK, N. Y., A CORPORATION OF DELAWARE.

SPEED-STARTING DEVICE FOR MOTORS.

1,300,624.

Specification of Letters Patent. Patented Apr. 15, 1919.

Application filed March 1, 1918. Serial No. 219,846.

To all whom it may concern:

Be it known that I, EMILE LABRÉLY, a citizen of France, and a resident of Paris, France, have invented certain new and useful Improvements in Speed-Starting Devices for Motors, of which the following is a specification.

This invention relates to a device for quickly setting motors into rapid operation. 10 In the form shown herein it is applied to a phonograph motor. When a phonograph is set into operation in the usual way, as by releasing the turntable, it does not get up its proper speed until the turntable has 15 made a number of revolutions, and for this reason the tone or quality of the sound reproduction is apt to be poor at the commencement of playing and for an appreciable interval thereafter and correct reproduction is not obtained until the record tablet, which may be cylindrical or of disk form or of other forms, has gotten up the proper speed. The invention, however, may 20 be applied to other motors and is not limited to use with a phonograph.

In the drawings forming part of this specification, Figure 1 is a plan view of one embodiment of my invention and showing a portion of a phonograph to illustrate its 30 connection therewith. Fig. 2 is a vertical sectional view taken on line 2, 2, Fig. 1. Fig. 3 is a view similar to Fig. 2 and showing the clutch members in coacting relation, and Figs. 4 and 5 are partial sectional views 35 taken on the line 4, 4, Fig. 2 and showing in dotted lines two positions of a sector with respect to an arm on the governor of the motor.

Only enough of the motor is shown in the 40 drawings to illustrate the connection therewith of the starting apparatus of the present invention. The reference numeral 10 designates the turntable shaft of a disk phonograph, and 11 a spur gear secured to 45 the shaft 10 and rotating therewith. A gear 12 on the shaft 13 meshes with the gear 11 and the governor 14 is operated through a gear 15 on its shaft 16 meshing with a gear 17 on the shaft 13. The speed starting device is illustrated in connection with the 50 shaft 13 and preferably comprises means for setting the shaft 13 into rapid rotation, said means being automatically disconnected when the shaft 13 comes up to speed. In 55 the form shown the shaft 13 has a clutch

member 18 secured thereto and rotating therewith, and a coacting clutch member 19 turns and slides loosely on the shaft 13. The sleeve or stop member 13' on the shaft 13 serves to support the clutch member 19 in its lowermost position. Means are provided for rotating the clutch member 19 and also for throwing it into engagement with the clutch member 18 on the shaft 13, and in the form shown the clutch member 19 is provided with or has formed thereon a spiral gear 20 having angularly arranged teeth 21 characteristic of a spiral gear, and a rotating member having spiral gear teeth of such form as to coact with the gear teeth 21 of the gear 20, is provided. In the form shown such gear member consists of a sector 22 having inclined teeth 23 on the circular portion of its periphery. The arrangement is preferably such that the gear teeth 21 and 23 continue to engage, notwithstanding bodily movement on the shaft 13 of the gear 20, and for this purpose in the form shown the gear 20 is made thicker than the sector 22. The relation of the inclined gear teeth 21 and 23 is such that the thrust, due to the spiral character of the teeth, upon the gear 20 is toward the clutch member 18, tending to bring the driving clutch member 19 into contact and engagement with the driven clutch member 18.

As the gear 20 turns freely on the shaft 13, it is desirable to provide means for resisting to some extent the rotation of the gear 20, so that the work done in rotating 90 the gear 20 from the sector 22 shall be sufficient to produce a thrust component large enough to cause the gear 20 to slide upon the shaft 13 and thereby to bring the clutch members into engagement. This result may 95 be secured in a number of ways, but in the form shown a resilient member is resorted to for resisting rotation of the gear 20 and has the form of a flat spring 24, bearing against the driving clutch member 19. This 100 spring 24 is preferably of substantial width so that it is maintained in contact with the gear 20 during the sliding movement of the latter on the shaft 13. Said spring 24 may be secured to the bracket 25 which is provided for affording a support for the bearing screw 26 of the sector 22, and which may be attached to any convenient supporting means, such as a portion of the motor frame 27.

Conveniently accessible manually operable means for rotating the sector 22 are provided, and the same preferably extend to the exterior of the phonograph or other cabinet or device 28. In the form shown a handle 29 is provided passing through an aperture 30 in the wall of the cabinet 28, and secured thereto is a slide member 31 which may be mounted in any convenient way for sliding, as, for example, it may have a slot 32 in which is received a bolt or screw 33 which may be mounted in any suitable support as a bracket 34. The slide 31 is connected to the sector 22 so that when said slide 21 is moved longitudinally by the handle 29, rotary movement is imparted to the sector 22. In the form shown the sector 22 has an arm 35 provided with a slot 36, and the slide 31 is provided with a screw 37 firmly secured thereto and adapted for longitudinal movement in the slot 36. Other forms of connection between the slide 31 and the sector 22 may be resorted to for the purpose named, or the member 31, if desired, may be mounted in other forms of supports than that shown so that, for example, it may move laterally as well as have direct sliding movement.

The structure so far described is well adapted for use with the ordinary phonograph having the ordinary so-called starting means which consists only of a releasing lever adapted to be held in contact with or moved away from the turntable. Movement of the handle 29 to impart an initial spin to the motor may also serve to release the motor, leaving it free to operate. In the form shown means are operated from the handle 29 for stopping the motor by interposing a member in the path of the governor or part attached thereto, and for releasing the mechanism of the motor by being withdrawn from such path of movement. For this purpose I have shown a pin 38 secured to the sector 22 and extending in the path of an arm 39 secured to the shaft 16 of the governor 14. Such arm 39 is preferably of light spring wire and is preferably secured to the shaft 16 by being wound partially therearound and then inserted therein or fastened thereto so as to ease the shock when it strikes against the pin 38 to stop the motor. This is but one form of motor releasing and stopping means interconnected with the handle 29 and the motor spinning device of the present invention, and other modes of obtaining the same result may be resorted to within the scope of my invention.

The operation of the apparatus described will be readily understood from the foregoing. When the motor is at rest and the handle 29 is in corresponding position, here shown as the full-line position in Fig. 1 in which the handle 29 is pushed inward to its

limit of movement, the gear 20 is in substantially the position shown in Fig. 2, and the pin 38 is in contact with the arm 39 on the governor shaft, as shown in Fig. 4. Manual operation of the handle 29, as, in the form shown, by withdrawal to dotted line position in Fig. 1, removes the pin 38 from the neighborhood of the arm 39, the extreme removed position being substantially that shown in Fig. 5, and by coaction of the gear teeth 23 and 21, the gear 20 is rotated from the pinion 23. The movement of the gear 20, however, is resisted somewhat by the spring 24 so that coaction of the inclined gear teeth 21 and 23 produces a thrust action upon the gear 20, bringing the driving clutch member 19 into engagement with the driven clutch member 18, whereupon the rotation of the gear 20 is imparted to the shaft 13, setting the motor into rapid operation. The backs 40 of the clutch members 18 and 19 are preferably inclined substantially as shown so that as soon as the speed of the shaft 13, which is actuated not only by the gear 20 but also by the motor of the phonograph or other instrument, exceeds the speed of rotation of the gear 20, the gear 20 is backed off and the clutch members are automatically disengaged.

It will be seen that the device of the present invention affords efficient means for setting a motor into rapid operation, and that in the case of a phonograph, for example, superior reproduction effects can be obtained, as the phonographic tablet can be brought up to speed without any substantial interval during which the character of the reproduction is unsatisfactory due to the tablet traveling at a speed less than that at which it was intended to be reproduced. In this way it becomes possible to secure additional length of sound record without any increase in the size of the tablet, as the customary blank grooves left at the beginning of a record, before the sound undulations begin, and which are intended to permit the tablet to come up to speed before the sound undulations to be reproduced are encountered, may be substantially reduced in number and the sound producing undulations may begin practically with the commencement of the record groove, or at most within one or two turns of the end of the groove.

It will be understood that the apparatus herein disclosed is intended only to illustrate my invention and to afford a clear understanding thereof, and that I am not confined thereto but may resort to such changes and modifications as are included within the scope of my claims by which the invention is defined.

I claim:

1. The combination with a motor comprising a shaft and driving means therefor, of

- means for accelerating the movement of said shaft comprising a fixed clutch member and a sliding clutch member, and a pair of spiral gears, the driven gear of said pair serving 5 both to rotate the sliding clutch member and to slide same on said shaft into coaction with the other clutch member, the clutches being adapted to be automatically disconnected when the speed of the fixed clutch member 10 exceeds that of the other clutch member.
2. In a motor starting device, a driven clutch member, a driving clutch member, means for rotating said driving clutch member and imparting thereto a thrust in a direction toward said driven clutch member, 15 and means for resisting rotation of said driving clutch member.
3. In a motor starting device, a driven clutch member, a driving clutch member, 20 means for rotating said driving clutch member and imparting thereto a thrust in a direction toward said driven clutch member, and spring means for resisting rotation of said driving clutch member.
4. In a motor starting device, a driven clutch member, a driving clutch member, means for rotating said driving clutch member and imparting thereto a thrust in a direction toward said driven clutch member, 25 and a spring bearing against said driving clutch member for retarding the rotation thereof.
5. In a motor starting device, a shaft, a driven clutch member fixed to said shaft, a 30 driving clutch member rotatable and slidible on said shaft, a spiral gear on said driving
- clutch member, a second spiral gear meshing with the first-named spiral gear, the teeth of said gears being inclined to thrust said driving clutch member toward said driven 40 clutch member, means for rotating the last-named spiral gear, and spring means for retarding rotation of said driving clutch member.
6. In a motor starting device, movable 45 means for imparting an initial spin to the motor, means whereby same is automatically released as the speed of the motor increases, and means connected therewith and adapted in one position thereof to extend within the 50 path of a movable element of the motor, and when operated to spin the motor to be withdrawn from such path of movement.
7. In a motor starting device, a shaft, a driven clutch member fixed thereon, a driving clutch member free to turn and slide on said shaft, a spiral gear on said driving clutch member, a spring bearing against said spiral gear, a sector having spiral gear teeth adapted to coact with the first-named spiral 55 gear, an arm projecting from said sector into the path of a movable element of the motor and adapted, when the sector is turned to rotate said driving clutch member, to be withdrawn from the path of movement of 60 such element, and means including a slide and a handle for imparting rotary movement to said sector.

In testimony that I claim the foregoing, I have hereto set my hand, this 23rd day 70 of February, 1918.

EMILE LABRÉLY.
